CLAM BUCKET

Clarence Sollis, O'Fallon, Ill.

Application May 22, 1936, Serial No. 81,326

1 Claim. (Cl. 37—184)

This invention relates to new and useful improvements in what is generally known as clam shell buckets.

The principal object of the present invention is to provide a bucket of this character which will actually dig into the material being handled instead of scraping along the top thereof as occurs with present day types of buckets.

Another important object of the invention is to provide a bucket which is constructed in such a manner as to be capable of actually cleaning a surface of all material to be loaded.

Still another important object of the invention is to provide a clam shell bucket which because of its sturdy construction will not be susceptible to the ready development of frequent defects.

Other important objects and advantages of the invention will become apparent to the reader of the following specification.

In the drawings:

20 Figure 1 represents a side elevational view of the bucket with the shell sections in vertical section;

25 Figure 2 is a side elevational view of the assembly with the shell sections in open position;

Figure 3 is a back elevation of the assembly;

Figure 4 is a fragmentary vertical sectional view on line 4—4 of Figure 1;

Figure 5 is a top plan view of the frame;

Figure 6 is an enlarged vertical section on line

30 6—6 of Figure 3;

Figure 7 is a top plan view of the slider;

Figure 8 is a section on line 8—8 of Figure 1.

Referring to the drawings wherein like numerals designate like parts, it can be seen that

35 numeral 5 represents the hoist frame consisting of the vertical side members 6—6 and the cross straps 7—7 connecting the upper ends thereof. Mounted between the straps 7—7 are the rollers

40 8—8 while upon the straps 7—7 are the cross members 9—9 between which a plurality of rollers 10 are mounted. The cables 11—12 pass between these rollers 8—10, the rollers serving as anti-frictional means.

45 An elongated pin or shaft 13 extends through the lower portions of the frame members 6—6 and this shaft 13 extends through the apices of the side walls 14 of the clam shell sections 15—15, and on one of these sections 15 eye members 16

50 can be provided and to which cables can be attached for steering the bucket while the same is in operation.

A pair of plates 17—17 have their ends secured to the side members 6—6 at the lower portions

55 thereof, and between these plates 17—17 is the

cage 18 in which the pulleys 19—20 are mounted. As shown in Figures 3, 4, and 7, numeral 21 represents the slider which consists of the plates 22—22 spaced apart by the blocks 23—23, leaving end portions 24 for disposition over opposite side portions of the side members 6—6 of the frame 5. Within the slider 21 is mounted the plate member 25 which at one end is provided with the eye 26 to which the lift cable 11 is secured. The other end of the plate 23 has the shaft 27 of the pulley 28 disposed therethrough, this pulley 28 overlying the pulleys 19—20.

The cable 12 which controls the sections of the bucket extends downwardly under the pulley 19 and then up over the pulley 28, and then downwardly under the pulley 20 from where it extends to be anchored, as at 29, to one of the plates 17. It is of course to be understood that any other form of block and tackle can be employed, depending upon the character of work to be executed with this bucket.

Ears 30 arranged in pairs on the outsides of the plate 17 have the upper ends of the links 31 pivotally connected thereto, while the lower ends of the links 31 are pivotally connected to ears 32 on the bucket sections 15—15.

It can now be seen that with the sections of the bucket open in the manner shown in Figure 2, the assembly is lowered by the cable 11 into the material to be loaded and when it reaches the material, the lift cable 11 is released and pull is then exerted on the bucket cable 12. This pull on the cable 12 causes a downward movement of the slider 21 on the frame 5 and this motion imparted by way of the links 31 will cause contraction of the bucket sections 15 as they make a sweep through the material under the weight of the entire assembly. In this manner an actual digging into the material is executed by the bucket sections instead of a mere scraping operation which generally occurs with most types of buckets.

While the foregoing specification sets forth the invention in specific terms, it is to be understood that numerous changes in the shape, size, and materials may be resorted to without departing from the spirit and scope of the invention as claimed hereinafter.

Having described the invention, what is claimed as new is:

A bucket assembly of the character described comprising a frame provided with a slider thereon and having side portions, a pair of bucket sections pivotally mounted on the frame, a lift cable connected to the slider, a bucket control

ling cable extending into the slider, a pulley stationarily mounted on the frame under which the said bucket cable extends, the frame end of the bucket cable being anchored to the slider, link members between the slider and the bucket sections, said slider consisting of a pair of plates provided with spacer blocks between the same inwardly of the ends thereof to define guideways

at the end of the slider and an intermediate passageway for the disposition of the cables, the end portions of the said plates overlapping the side portions of the frame, and pivotal link members between the slider sections and the bucket sections.
